DISPLAY DEVICE

Stanley Lowen, New York, N. Y.

Application May 13, 1931. Serial No. 536,990

3 Claims. (Cl. 206—44)

This case relates to novelty devices.

In general, the object of the invention is to provide a combined shipping and display device for an article.

5 More specifically, the object is to provide a device which holds an article in one position for display purposes and in another position for shipping purposes.

Further, the object is to provide a novel display device made of semi-stiff, flexible material such as cardboard.

Still further, the object is to build up a rigid device in sections and assemble them into a unit after they have been individually built up.

15 Another object is to form a display or shipping device out of channeled members.

Other objects and advantages will be herein-after brought out in the description and in the claims and will be obvious from the drawing 20 wherein

Fig. 1 is a front view of the device in readiness to be shipped;

Fig. 2 is a similar view with the cover open and the article in display position;

25 Figs. 3 and 4 are sections on lines 3—3 and 4—4 of Fig. 1, respectively, and

Fig. 5 is a section on lines 5—5 of Fig. 2.

Referring to the drawing in detail, the device consists primarily of three distinct sections 30 which may be termed the base section, the intermediate or article carrying section, and the enclosing or housing section.

35 *Base section.*—The base consists of a hollow member made in two parts, a bottom part 16 and a top part 11 fitting into the part 10. The top part has an opening cut out to leave inwardly extending marginal portions. The parts are glued to each other or fastened in any other suitable way. Preferably, they are made of cardboard material but if desired any other material 40 may be used.

45 *Intermediate section.*—The intermediate section consists of a platform or support 12 made of cardboard formed into a hollow or channeled member. On top of this member is glued one fold 13 of a hinge made in three folds out of card material. The hinge may be made of other material such as metal. The intermediate fold 14 connects fold 13 to a fold 15 glued to an article 50 holder 16. The use of this hinge furnishes a great degree of flexibility to the movement of the member 16, permitting it to move to a position where the folds are substantially in the same plane or where they are practically one 55 above the other. Obviously, the hinge may be

made of any other suitable material than card material. Member 16 is formed of a single blank of card material originally of the same width throughout. The sides of this blank are slit horizontally from opposite sides and the upper portions above the slits bent back substantially at right angles to the face of member 16 to form tabs 17, leaving an upper face portion 18 narrower than the lower face portion. The member 16 is designed to carry an article attached to it 60 in any suitable manner as by a strap 19 passed around the face and tabs of the member. The strap is held against downward movement by engagement with the upper outwardly extending edges of the wider face portion of member 16. 65 Tabs 17 also serve by engagement with the lower hinge fold to space the article holding member from the platform when the member is in the retracted position shown in Fig. 4.

70 The platform rests on the bottom of an oblong angle piece 20 in such a position that the vertical long side of the angle piece and the adjacent side of the platform are spaced from each other to leave a passage 21 for a purpose to be brought out later. The bottom of the platform is glued 75 to the bottom of the angle piece.

75 *Housing sections.*—The housing section comprises vertical end portions 24 arched at the top and an intermediate portion 25 connecting the end portions and bent into the shape defined by 80 the tops and sides of the end portions. The portion 25 has an arched opening 26 in the front. The portions 24 and 25 are of cardboard material and may be made up of a single blank or of several parts as desired. Attached to the inner sides 85 of the end portions 24 are similarly shaped but smaller pieces 27 leaving a guideway 28 between the periphery of each piece 27 and the interior surface of the intermediate portion 25. Within the guideways 28 extend the sides of a closure 90 member consisting of a corrugated part 29 bent to a curve similar to the arched tops of end pieces 24. Part 29 is attached to a similarly curved backing part 30, both being made of slightly flexible cardboard material so that they tend to 95 resume their initial flat unbent form. As a result, when inserted into the passageways 28 by which it is slidably guided, the closure member presses outwardly against the interior surface of the portion 25 of the housing. The consequent 100 friction holds the closure member in any position to which it is adjusted. The member may be moved in front of opening 26 as in Fig. 1 or may be moved upwardly to expose the opening as in

Fig. 2.

The housing section being complete, it is placed around the intermediate section in contact with the rear vertical side of the platform 12 to which it is glued. The housing and intermediate sections are now in effect a rigid unit. This unit is placed into the base through the opening in the top of part 11 and glued to the bottom of part 10, the opening locating the unit in proper position. The horizontal top marginal portions of the base hold the unit rigidly against tendency to move laterally relative to the base. By making the base and platform hollow or channeled, the construction and assembly are simplified at the same time providing rigidity to the device.

15 The assembly is now complete. As shown in Figs. 1 and 4 the device is ready for shipping the closure member is down, the lower edge entering the passage 21 between the vertical side of angle piece 20 and the adjacent side of the platform 12. The device is then ready for packing and shipping. As shown in Figs. 2 and 5, the closure member is up and the article carrying member moved to inclined position with the forward portion extending out of the housing and resting on the base.

20 While the invention has been described with reference to a single preferred embodiment, it is understood that the invention is not restricted to any particular form or material but may be varied within the scope of the invention without departing therefrom. I therefore desire to be limited only by the scope of the following claims.

25 I claim:

35 1. A device comprising a member adapted for

holding an article, a support to which said member is secured for movement into different positions on the support, a housing for said member to conceal and protect said member when in one position and having an opening through which the member is movable to display position exterior of the housing adapted to be assembled with said support, and a hollow base above which said housing extends and within which the assembly of said support and housing is insertible as a unit and to which it is fastened.

2. A portable device comprising a member adapted to hold an article, a support means for mounting said member on said support for movement into different positions, a housing for said member connected with the support and having an opening through which the article holding member may be viewed and through which said member is adapted to be moved to outside position, and a cover carried by the housing and movable thereon to a position in front of said opening to conceal and protect said member when in a position inside said housing.

3. A device comprising an article holder, a housing therefor, a frame on which the housing is rigidly mounted, a platform provided on the frame, a hinge connection between said platform and said holder for adapting the latter to move from a position in said housing to a position outside the housing, said frame having a part rigid therewith, extending beyond the front of said housing to provide a rest for said holder when in outside position.
